US00D616309S

(12) **United States Design Patent**
Toh et al.

(10) **Patent No.:** **US D616,309 S**
(45) **Date of Patent:** ** *May 25, 2010

(54) **CONTAINER**

(75) Inventors: **Kiat Cheong Toh**, Forest Hills, NY (US); **Sergio Gedanke**, Brooklyn, NY (US); **Ravi Varma**, Encinitas, CA (US)

(73) Assignee: **Colgate-Palmolive Company**, New York, NY (US)

(**) Term: **14 Years**

(21) Appl. No.: **29/334,438**

(22) Filed: **Apr. 20, 2009**

Primary Examiner—Carol Rademaker

(74) *Attorney, Agent, or Firm*—Amy M. Fernandez

(57) **CLAIM**

The ornamental design for a container, as shown and described.

DESCRIPTION

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawing views are included for the purpose of showing environmental structure that forms no part of the claimed design.

1 Claim, 6 Drawing Sheets
